UNITED STATES PATENT OFFICE.

WALTER CHEETHAM, OF OAKLAND, CALIFORNIA, ASSIGNOR, BY MESNE ASSIGNMENTS, TO GEORGE D. BROWN, OF PASADENA, CALIFORNIA.

CREMATION-FURNACE.

1,147,310.

Specification of Letters Patent. Patented July 20, 1915.

Application filed March 18, 1913. Serial No. 755,122.

To all whom it may concern:

Be it known that I, WALTER CHEETHAM, a citizen of the United States, and a resident of the city of Oakland, county of Alameda, 5 and State of California, have invented certain new and useful Improvements in Cremation-Furnaces, of which the following is a specification.

The invention relates to furnaces such as 10 are used for the cremation of bodies.

The object of the invention is to provide a furnace in which the heat is applied first to that part of the body which possesses the greatest heat resisting properties.

Another object of the invention is to provide a furnace which operates with rapidity 15 and efficiency to crenate bodies.

The invention possesses other advantageous features, which, with the foregoing, 20 will be set forth at length in the following description, where I shall outline in full that form of the invention which I have selected for illustration in the drawings accompanying and forming part of the present 25 ent specification. The novelty of the invention will be included in the claims succeeding said description. From this it will be apparent that I do not limit myself to the showing made by said drawings and description, as I may adopt many variations 30 within the scope of my invention as expressed in said claims.

Referring to said drawings: Figure 1 is 35 a rear view of the furnace with the doors removed. Fig. 2 is a horizontal cross section of the furnace taken on the line C—C Fig. 3. Fig. 3 is a transverse cross sectional elevation of the furnace taken on the line A—A Fig. 2. Fig. 4 is a longitudinal 40 cross sectional elevation taken on the center line B—B of the furnace.

The furnace consists of a structure of 45 brick or other fire and heat resisting materials having a top 2 and side walls 3 of sufficient thickness to conserve and retain the heat in the furnace. Within the furnace and preferably extending therethrough from end to end is a chamber or retort 4 for the reception of the body. The retort 50 chamber is provided at its front and rear ends respectively with doors 5—6 which are provided with suitable means so that they may be readily raised and lowered. Lying on the floor 7 of the retort chamber 4, at opposite sides thereof are channel irons 8 upon

which the rollers which support the casket rest.

Below the retort chamber, and preferably at opposite sides of the center thereof are chambers 9 opening at the rear of the furnace, in which the fire for producing the desired heat is arranged, preferably at the rear end of the chambers or fire boxes. Below the fire boxes 9 and separated therefrom by grates 26 are the ash pits 12.

Between the chambers 9 and below the center of the retort chamber 4 is a chamber 13, closed at its front end by the front wall of the furnace and open at its rear end. The dividing walls 14 separating the chamber 13 from the fire boxes are cut away at the front end, forming apertures 15 through which the heat from the fire passes into the chamber 13.

The floor 7 of the retort chamber 4 is provided with an aperture or apertures, preferably in the form of a slot 16, through which the heat enters the retort chamber from the chamber 13. The slot 16 extends longitudinally of the retort chamber from 80 a point adjacent the front end thereof, substantially along its center line, and is usually made about five feet in length, although this length may be varied.

The casket is placed in the retort chamber 85 from the front and rests directly above the slot 16. The heated air and gases of combustion entering through the slot are, therefore, directed against the back of the body, subjecting that part, which is generally the last to 90 be cremated, to the greatest heat. By thus directing the heat directly against the most resistant part of the body, that part is consumed at the same time as the less resistant parts, thereby greatly shortening the time 95 required for cremation. As the body is destroyed, the ashes fall through the slot 16 into the chamber 13 from which they are later withdrawn.

The smoke and hot gases from the retort 100 chamber pass through the flues 17, arranged in a circuitous path in the top of the furnace, to the stack 18, whence they are discharged. A damper 19 in the stack regulates the draft therein. The flues 17 are arranged in the top of the furnace for the purpose of heating the same, which heat is utilized to raise the temperature of the air which is fed to the fires and retort chamber.

The back of the furnace is provided with 110

hinged doors, which when closed, cover the openings of the fire boxes, ash pits and chamber 13, so that all noise due to the roar of the fire is substantially eliminated, and to prevent the inrush of cold air which would reduce the temperature of the retort chamber.

Air for the fires is supplied by the blower 21 which drives the air through the circuitous passage 22 arranged in the top of the furnace, and through the vertical passages 23 extending downward at the rear of the furnace and opening into the ash-pits. The air in passing through these passages becomes pre-heated and the temperature of the fire raised accordingly. Arranged in the sides of the retort chamber 4 are apertures 24 connecting the retort chamber with the passages 23, said apertures being controlled by dampers 25, which are moved by any suitable means. These apertures 24 occur adjacent the top wall of retort chamber at different heights, so that air may be admitted into the chamber at different levels. Air is admitted through the apertures 24 to cause the consumption of the smoke in the retort chamber and prevent it from being discharged from the stack. By admitting the air at different levels adjacent the top of the chamber, I have found that the smoke is consumed to a greater extent than if the air were admitted at one aperture. When the cremation process is well under way, the dampers 25 may be opened and the rear door of the retort chamber partly raised, thereby producing a false draft which reduces the rate at which the fuel is being consumed, and thereby creating a considerable saving in fuel.

It is to be understood that I do not limit myself to the construction shown in the drawings, or to the use of two fire boxes, since it is evident that one fire box of larger capacity may be employed and that various other changes in construction may be made without departing from the spirit of my invention.

I claim:

1. A crematory furnace comprising a furnace chamber, a floor for said chamber, a fire box below the floor, said floor being formed a substantial portion of its length with a narrow longitudinal slot through which the heat passes from the fire pit upward against the casket, thereby concentrating the heat at this point the remaining portion of the floor of said chamber being imperforate and an exit tue leading from the end of the furnace chamber opposite the end thereof in which said slot is located.

2. A crematory furnace comprising a furnace chamber, a floor for said chamber, the chamber being formed with a vertical flue at the rear, said floor being formed with a central narrow longitudinal slot for substantially the front half portion of its length the remaining portion of said floor being imperforate, a fire pit below the rear portion of said floor, said fire pit communicating with said slot and vertical floor supports under the slotted floor portion.

In testimony whereof, I have hereunto set my hand at Oakland, California, this seventh day of March 1913.

WALTER CHEETHAM.

In presence of—
J. W. ALBRIGHT,
H. G. PROST.
